IRVING W. BRINGMANN, OF PITTSBURGH, PENNSYLVANIA, ASSIGNOR TO THE ALUMINUM COOKING UTENSIL COMPANY, OF NEW KENSINGTON, PENNSYLVANIA, A CORPORATION OF PENNSYLVANIA

JACKETED VESSEL

Application filed November 21, 1932. Serial No. 643,691.

This invention relates to the construction and manufacture of double-walled vessels. It relates particularly to an improved inlet assembly for steam-jacketed kettles and the like.

In the past, particularly in certain localities, difficulties have been encountered in the operation of steam-jacketed kettles and other double-walled vessels due to the deterioration of one or both walls, and especially the inner wall, near the point of introduction of the steam or other fluid with which the jacket is filled. This deterioration is usually caused by corrosion, or by erosion due to the entrainment of solid particles in the steam, or by one or both of these factors combined with localized overheating at or near the point against which the entering steam impinges. As a result of this deterioration it sometimes happens that a wall failure occurs, necessitating replacement or expensive repairs long before the end of the normal useful life of vessels of this type.

The primary object of my invention is to provide an inlet assembly for double-walled vessels which protects at least one of the walls of the vessel from deterioration by erosion, corrosion, localized overheating, and analogous destructive factors.

A second object is to provide an improved inlet assembly for jacketed vessels which is economically constructed and assembled, and quiet in operation.

My invention has for further objects such other operative advantages and results as are found to obtain in the structure described hereinbelow with reference to the accompanying drawing, in which:

Fig. 1 is an elevational view, with parts broken away, of a steam-jacketed kettle with my improved inlet assembly in place therein;

Fig. 2 is an enlarged sectional view of the inlet assembly applied as in Fig. 1;

Fig. 3 is a vertical sectional view of a preferred form of the tubular inlet member or nozzle employed in my inlet assembly;

Fig. 4 is a top plan view of the inlet member shown in Fig. 3; and

Fig. 5 is another vertical sectional view of a portion of the inlet member, taken on the line V—V in Fig. 3.

Referring to the drawing, in which like reference numerals have been used throughout to denote like parts, my improved inlet

assembly consists essentially of a tubular inlet member or nozzle 1, a concave inner baffle plate 2 provided with a centering pin or guide pin 4, and an outer baffle plate 6 which may sometimes be omitted. The inner baffle or plate 2 is held in a fixed position relative to the inlet member 1 and the inner wall or shell 7 of the vessel by the guide pin 4, which preferably extends through the plate 2 and is connected thereto by welding or brazing 8, or other suitable connecting means. The pin 4 extends outwardly from the surface of the plate and through an aperture 10 which is preferably centrally disposed in a bridge element 11 extending across the orifice or discharge opening 12 in the nozzle 1. The radius of curvature of the plate 2 is preferably less than the radius of curvature of the portion of the inner wall 7 which it covers, to give the plate a resilient character, and when this construction is employed all tendency for the plate to vibrate noisily or "chatter" during use is eliminated because of the tension under which it is held in place. The baffles 2 and 6 are both preferably circular in form, but may be elliptical or of other suitable shape.

When the lower or outer baffle plate 6 is employed, it is preferably applied directly to the inner surface of the outer shell 14 of the vessel and in close contact therewith, as shown. This plate is formed with a central aperture coinciding with the aperture in the outer shell through which steam or other fluid is admitted, and the edge 15 of the plate aperture may conveniently be spun or otherwise turned down around the edge of the shell aperture to secure the plate 6 in the desired position. Other means of holding the plate in position may be substituted if preferred, however. An internally threaded member 16, in which the nozzle 1 seats, is welded or otherwise secured to the outer shell surrounding the inlet aperture.

The baffle plates 2 and/or 6 may be fabricated from the same metal as the vessel itself, or from a different metal. The metal selected for this purpose in any given case depends on the conditions under which the vessel is to be used and the nature of the destructive factors encountered; i. e., whether corrosion or erosion is the more serious. This in turn frequently depends on the source and nature of the fluid used in the jacket, and the amount and nature of the solids con-

tained therein. In general, however, baffle plates of copper, aluminum, or alloys thereof are satisfactory. For example, I have found that in some localities steam-jacketed kettles 5 made of aluminum and provided with hard copper baffles give very good results.

One feature of my invention is that the assembly of a double-walled vessel embodying the improved inlet is very simple. Prior 10 to sealing the outer wall or jacket 14 to the inner wall or kettle 7, the outer baffle 6 is applied, if it is to be used, and the inner baffle 2 is inserted between the walls with the guide pin 4 extending through the inlet opening 15 in the outer wall. No welding or other securing of the baffle 2 is necessary. After the jacket is secured in place, the nozzle 1 is screwed into the seat or socket 16, care being taken that the guide pin 4 passes through 20 the aperture 10 in the bridge 11 across the nozzle orifice 12. When the nozzle is screwed tightly into place, the bridge member 11 presses against the portion of the baffle 2 surrounding the guide pin 4, and holds the edges 25 of the baffle tightly against the inner wall 7 of the vessel. The completed vessel is then customarily mounted on legs or a stand 18, and is ready for use. When steam or other fluid is admitted to the jacket through the 30 nozzle 1, it strikes the baffle 2 and is thus prevented from impinging directly on the inner wall 7. The outer wall is also protected by the baffle 6. When the bridge member 11 has the preferred form shown in the 35 drawing, the nozzle discharge orifice 12 is divided into two angularly disposed orifices. As a result the entering fluid is diverted from a path normal to the surface of the baffle 2 and the inner wall 7, and the life of the baffle 40 and the vessel walls is therefore further prolonged.

While my invention has been described with special reference to a preferred embodiment thereof, it is to be understood that this 45 embodiment may be variously modified within the scope of the appended claims.

What I claim is:

1. In a double-walled vessel, a detached baffle plate positioned between the walls to 50 protect the inner wall and having a guide pin secured thereto and extending through the outer wall.
2. In a double-walled vessel, a baffle plate positioned between the walls and partially 55 in contact with the inner wall and having a substantially rigid guide pin extending from its outer surface through an aperture in the outer wall of the vessel.
3. In a double-walled vessel, a curved baffle 60 plate positioned between the walls with its edge in contact with the inner wall, said baffle having a smaller radius of curvature than the portion of the inner wall covered thereby and being held against the inner wall by a mem- 65 ber adjustably attached to the outer wall and

bearing against said baffle substantially at its center.

4. In a double-walled vessel, a baffle plate 70 between the walls provided with an outwardly extending guide pin, and a member supported by the outer wall which engages said guide pin and holds the baffle against the inner wall.

5. In a double-walled vessel, a curved baffle plate 75 between the walls adjacent the inner wall, a guide pin secured substantially at the center of said baffle and extending outwardly therefrom, and a member supported by the outer wall and provided with an aperture 80 adapted to receive said guide pin to hold said baffle plate in the desired position relative to said member.

6. In a double-walled vessel, a baffle plate secured thereto and extending outwardly 85 therefrom through an aperture in the outer wall, and an inlet member mounted in said aperture and engaging said guide pin to hold said baffle plate in the desired position relative to said inlet member.

7. In a double-walled vessel, an externally 90 convex substantially circular baffle plate positioned between the walls with its edge against the inner wall, a guide pin secured substantially at the center of said baffle plate 95 and extending outwardly therefrom, and a tubular inlet member extending through an aperture in the outer wall and having at its inner end means for engaging said guide pin and pressing said baffle plate against the inner 100 wall.

8. In a double-walled vessel, an externally 105 convex substantially circular baffle plate positioned between the walls with its edge against the inner wall, a guide pin secured substantially at the center of said baffle plate and extending outwardly therefrom, and a nozzle 110 adjustably mounted to extend through an aperture in the outer wall, said nozzle having at its inner end an element provided with an aperture through which said guide pin extends, said element holding said baffle against the inner wall.

9. An inlet assembly for jacketed vessels, 115 comprising a tubular inlet member extending through an aperture in the outer wall of the vessel and provided at its inner end with an element having a port therein, an externally convex baffle with an outwardly extending 120 guide pin secured thereto and extending through said port, said baffle being held against the inner wall of the vessel by the said element on the inner end of the inlet member, and a second baffle plate covering the inner 125 surface of the outer wall of the vessel adjacent the aperture therein.

In testimony whereof I hereto affix my signature.

IRVING W. BRINGMANN.
